UNITED STATES PATENT OFFICE.

GEORGIA A. POST, OF FOREST HILLS, NEW YORK.

GAME.

Application filed March 24, 1921. Serial No. 455,277.

To all whom it may concern:

Be it known that I, GEORGIA A. Post, a citizen of the United States, and resident of Forest Hills, county of Queens, and State 5 of New York, have invented an Improvement in Games, of which the following description, in connection with the accompanying drawings, is a specification, like letters on the drawings representing like parts.

10 My present invention relates to games, and more particularly to a game and game apparatus having an educational value in addition to its value as a means for amusement.

15 Young people are always interested in games, though heretofore it has been found difficult to keep them interested in educational games, the principal reason being that educational games are too apt to stress 20 the educational side of the game. I have found that all young people are interested in stories that may be told to them, such for instance, as the well known children's classics, as Little Red Riding Hood, Little

25 Goldilocks, and the like. Children do not, however, take such a keen interest in such stories if they have to do the reading themselves, and this is particularly true if the story is of any considerable length. They 30 do however, love to play games, and I have, in my present invention, devised a game in which a story, particularly a children's story, may be made the subject of the game.

As the game is interesting in itself, there is 35 no difficulty in maintaining the interest of the children, and as the playing of the game requires, or presupposes, a knowledge of the story, they will read the story—on which the game is founded—not only once, but 40 repeatedly, thus acquiring knowledge rapidly and naturally. The apparatus for playing the game may be as simple or as complex as may be desired, though it will be obvious that simplicity in construction

45 is to be preferred, provided the construction is rugged.

The principal object of my invention therefore, is an improved game and apparatus therefor.

50 Another object is an improved game combining educational and amusement qualities. Other objects and novel features of the construction and arrangement of parts will appear as the description of the invention 55 progresses.

In the accompanying drawing illustrating the preferred embodiment of my invention,

Fig. 1 is a pictorial illustration, in elevation, of the game apparatus adapted to play 60 the story of The Three Bears.

Fig. 2 is a rear elevation of one of the characters of the game to be played, and

Fig. 3 is a side elevation of Fig. 2.

Referring to the drawing, 10 designates 65 a dwelling house, in cross section, exposing various rooms 11, 12 on the lower floor and rooms 13, and 14 on the upper floor, a stairway 15 leading from the room 12 on the lower floor to the room 14 on the upper 70 floor. Starting at a point outside the house 10 is a slot or groove 16 leading from a siding 21 in which may be stored or positioned figures, such as 17, and with which the game is played. This groove 16 divides into two 75 parts, 18 and 19, the path 18 leading through the rooms 11 and 12 on the lower floor and provided at suitable intervals with cut-outs or sidings 20 in which the various figures 17 may be moved during the progress of the 80 game. This path 18 leads from the room 12 up the stairway 15 and thence through the rooms 14 and 13 and down through the path 19 to the groove 16, cut-outs or sidings 20 being provided in the path 18 in the rooms 85 13 and 14. The figures 17 are constructed of a block 22 having spaced apart therefrom a block 23 by a neck 24, the neck 24 sliding freely in the various paths and sidings, and prevented from removal therefrom by the blocks 22 and 23. The block 23 however, is small enough to drop into the siding 21. An upright 25 attached to the block 22 has pivotally mounted thereon one 90 of the figures 17 to be used in the game, the pivotal connection being utilized to place the figure in various positions to simulate the attitudes assumed by the characters in the story.

Assuming that the game to be played is 100 The Three Bears, the house 10 has its rooms 11, 12, 13 and 14 suitably furnished with a table 26, chairs 27, beds 28 and bed 29 respectively, while enough sidings 20 are provided to allow the various figures 17 to assume their proper positions. Reading from the story of The Three Bears, the player or players of the game move the various figures 17 to follow the story.

The game may be varied, of course, to 110

play any suitable story, but the above description will sufficiently illustrate the principles of my invention.

Having thus described my invention, what I claim as new is:

1. In an educational game, the combination of a pictorial illustration of a scene from a story, suitable fittings in said illustration to visually set forth the scene from 10 the story, a path leading through the scene, a plurality of sidings leading from said path, characters to simulate the characters in the story, and means for retaining said characters in the path.

2. In an educational game, the combination of a pictorial illustration of a scene from a story, suitable fittings in said illustration to visually set forth the scene from the story, a path leading through the scene, a plurality of sidings leading from 20 said path, pivotally mounted characters to simulate the characters in the story and allow them to assume various positions in the playing of the game, and means for retaining said characters in the path.

In testimony whereof, I have signed my name to this specification.

GEORGIA A. POST.
